CABLE CUTTER

Leslie A. Repscher and William C. Stratman, Los Angeles,
Calif., assignors to North American Aviation, Inc.

Application April 2, 1956, Serial No. 40,875

Term of patent 14 years

(Cl. D54—13)

Fig. 1 is a side elevational view of a cable cutter, showing our new design.

Fig. 2 is a front elevational view of the cable cutter as shown in Fig. 1.

Fig. 3 is an end elevational view of the cable cutter taken from the left or head end as shown in Fig. 2.

We claim:

The ornamental design for a cable cutter, substantially as shown.
